[57] CLAIM

The ornamental design for an eyeglass frame, substantially as shown and described.

DESCRIPTION

FIG. 1 is a perspective view looking from the top of an eyeglass frame, showing my new design;

FIG. 2 is a front elevational view of this frame;

FIG. 3 is a side elevational view of the frame looking from the left as viewed in FIG. 1, the view from the right as viewed in FIG. 1 being the same;

FIG. 4 is a front elevational view of the frame;

FIG. 5 is a top plan view looking down at the frame shown in FIG. 1;

FIG. 6 is a bottom plan view looking up at the frame.

FIG. 1.

FIG. 2.

FIG. 3.

FIG. 4.

FIG. 5.

FIG. 6.
